DESIGN FOR AN ELECTRIC FAN

Gustav H. Koch, Springfield, Mass., assignor to
Westinghouse Electric & Manufacturing Com-
pany, a corporation of Pennsylvania

Application August 14, 1937, Serial No. 71,089

Term of patent 7 years

To all whom it may concern:

Be it known that I, Gustav H. Koch, a citizen of the United States, residing at Springfield, in the county of Hampden and State of Massachusetts, have invented a new, original, and ornamental Design for an Electric Fan, of which the following is a specification, reference being had to the accompanying drawing forming part thereof, in which:

Figure 1 is a view in side elevation and Figure 2

a view in rear elevation of the electric fan showing my new design, the dominant portions of my design being shown in solid lines; and

Figure 3 is a perspective view of the electric fan.

I claim:

The ornamental design for an electric fan substantially as shown and described.

GUSTAV H. KOCH.
